SHOE IRON

Ernest C. Smeltzer, Indianapolis, Ind.

Application April 30, 1934, Serial No. 723,033

4 Claims. (Cl. 219—21)

My invention relates to improvements in shoe irons and particularly to an iron which is adapted for treating shoes after they have been finished for the purpose of removing wrinkles therefrom, and shrinking parts of the shoe which may be slightly large, ironing out wrinkles in the lining, etc.

It is one of the objects of my invention to provide an iron of the above character which is applicable to the shoe and which will permit the application of the iron to various parts of the shoe both inside and out.

For the purpose of disclosing my invention I have illustrated an embodiment thereof in the accompanying drawings in which

Fig. 1 is a side elevation of an iron embodying my invention;

Fig. 2 is a side elevation partly in section;

Fig. 3 is a view showing one application of my iron;

Fig. 4, a perspective view showing the manner of use of the iron over the toe of a shoe; Fig. 5, a view showing the manner of use within the toe of a shoe upon the under surface of the shoe top; Figs. 6, 7 and 8, views showing various positions of the tool within the toe of a shoe; Fig. 9, a view showing the manner of application of the tool to ensmall the opening into the shoe; and Figs. 10 and 11, views showing positions of the tool within the heel of a shoe.

In the embodiment of my invention illustrated the iron comprises a cylindrical tubular iron 1 having at its forward end a curve 2 formed therein and at its tip the end is flattened off as at 3. This curve formed in the iron preferably dips below the top plane of the base 4 of the iron and the tip with its flattened portion lies substantially in the same plane as the top edge of the base 4.

The base of the iron is preferably provided with a cylindrical socket 5 to receive a handle 6 which may be formed of bakelite or of a suitable insulating material, and even wood, if desired.

The iron is preferably heated by a suitable resistance element 7 which is inserted in the tubular iron and preferably extends throughout its length. This element is connected to a control switch 8 mounted in the handle and connected by a suitable conductor extending through the handle with one member 9 of a separable socket 10. The other member 11 is connected by a suit-

able lead with any desirable form of attachment plug.

In use the iron, after being heated, is applied to the shoe for the purpose of ironing out wrinkles therein or for the purpose of heating portions of the shoe for eliminating wrinkles or for shrinking that portion of the shoe slightly. Due to the peculiar shape of the iron, i. e., the curved neck with the flattened end, the iron lends itself to the various curvatures of the shoe so that close application of the iron may be obtained to various parts of the shoe and also the iron lends itself to insertion in the shoe and application to most any part of the shoe. Due to the flattened end and likewise the curved portion, the iron may be inserted in the shoe to reach clear up into the toe to remove any wrinkles occurring in the lining of the shoe.

Furthermore, the iron lends itself particularly advantageously to the shrinking of the top edge of oxfords, ladies' pumps, and other types of low shoes. Due to the curvature of the iron heretofore referred to, an even heat may be applied to the quarter lining for the purpose of reducing the quarter lining to draw in the top of the quarter for the purpose of making the shoe fit more snugly. Furthermore, due to the curvature and the flat tip, application of heat to the lining of the vamp is easily accomplished for the purpose of removing wrinkles or the like.

I claim as my invention:

1. A shoe iron for applying heat to a shoe comprising a cylindrical member having a curved neck, substantially as shown and described.

2. A shoe iron for applying heat to a shoe comprising a cylindrical member having a neck curved to lie below the plane of the top portion of the base of the iron substantially as shown and described.

3. A shoe iron for applying heat to a shoe comprising a cylindrical member having a curved neck curved to lie below the top of the base of the iron and having a flattened tip lying in a plane parallel with the plane of the base, substantially as shown and described.

4. A shoe iron comprising a hollow cylindrical iron having a curved neck lying below the plane of the top of the iron and having a flattened tip lying in a plane parallel with the top of the base of the iron and a resistance heating element arranged on the interior of the iron.

ERNEST C. SMELTZER.
